PACKAGE AND CONTAINER

Max T. Heller, Milwaukee, Wis., assignor to Mil-
print Products Company, Milwaukee, Wis., a
corporation of Delaware

Application September 3, 1929, Serial No. 389,944
Renewed September 8, 1933

2 Claims. (Cl. 206—46)

This invention relates to an improved package and container. The package herein disclosed is also disclosed in the companion application No. 352,635 of Charles G. Giese relating to a process and machine whereby this package may be manufactured commercially.

It is the primary object of the invention to provide a novel and improved package for foods in which substantial end caps of heavy paper, cardboard, or the like are held in spaced relation by the contents of the package and are secured together by a very light and preferably transparent sheet of flexible material connecting the end caps and hermetically sealing the contents of the package therewithin.

In the drawing:

Figure 1 is a perspective illustration of a partially completed package which, for purposes of illustration, is shown containing cookies.

Figure 2 is a perspective view showing a completed package of cookies in an upright position.

Figure 3 is a modified form of the invention showing in a view similar to Figure 2 a container completed and in which goods may be packaged subsequently to completion.

Like parts are identified by the same reference characters throughout the several views.

In the construction shown in Figures 1 and 2 the end caps or carton covers 6 and 7 which are used as headers for the improved package embodying the present invention, are spaced apart at a distance determined solely by the column of cookies 8 axially aligned therewith and confined therebetween. A sheet of very thin and preferably transparent fibrous material or paper like substance 9 having adhesive at 10 upon its margins is made to envelop the cookies as well as the outer peripheral portions of the headers 6 and 7 thereby hermetically sealing the edible contents

8 within the package. The cellulose material preferably employed for the sheet 9 is so thin and highly flexible that it allows the body to withstand any substantial strains. It has, however, very material tensile strength and since it holds the caps or headers 6 and 7 closely upon the ends of the stack of cookies at 8, the cookies themselves are so closely confined as to support the entire package against lateral or axial distortion.

The complete package possesses a very attractive appearance since its edible contents are even more clearly visible than they would be in glass

containers, and by virtue of the complete sealing of the flexible wrapper 9 to the caps 6 and 7 at its overlapping margins, the contents of the package are hermetically protected from moisture and deterioration.

In order to make such a container as that shown in Figure 3 it is necessary either to use a heavier grade of wrapper than that contemplated in the Figures 1 and 2 construction or else to take unusual precautions in the way of protecting the package against distortion. In the Figure 3 device the end cap 6' is centrally apertured at 11, the aperture being covered by a square of transparent paper 12 glued to the end cap over the aperture and preferably corresponding to the wrapper 9. It will be understood, of course, that the square 12 is not secured in place until the contents such as light weight candy or the like have been introduced through the opening at 11. A package completed by the introduction of food into the container shown in Figure 3 will have the same attractive appearance and other advantages which characterize the package shown in Figures 1 and 2 with the exception that the first described construction permits of a more rigid and substantial support of the end caps of the package from each other since the package is necessarily and completely full at the time of its construction.

I claim:

1. A substantially cylindrical package including a column of disc-like articles, each end of the column having a paper-like cupped cap having its flanges engaging over the column, the cap and contents adapted to serve as a mandrel during the manufacture of the package, and a wrapper wound about the column and secured to the flanges of the caps, the adjoining edges of the wrapper being also secured together.

2. A substantially cylindrical package including a column of disc-like articles, each end of the column having a paper-like cupped cap having its flanges engaging over the column, the cap and contents adapted to serve as a mandrel during the manufacture of the package, and a wrapper formed of thin, flexible and transparent material wound about the column and sealed to the flanges of the caps, the adjoining edges of the wrapper also being sealed together.

MAX T. HELLER.
